UNITED STATES PATENT OFFICE

2,226,795

REFRIGERATOR

Kurt E. Zeidler, Pittsburgh, Pa., assignor to Standard Railway Refrigerator Company, Chicago, Ill., a corporation of Delaware

Application January 5, 1939, Serial No. 249,473

7 Claims. (Cl. 62—17)

This invention relates to refrigerator cars used to transport perishable commodities at a pre-determined temperature. The essential features of such a car are an insulated structure and a refrigerating means for use in warm weather or a heating means for use in cold weather.

The invention relates particularly to refrigerator cars of the overhead bunker type. Cars of this type have the refrigerant containers suspended immediately below the roof. They are often provided with drip pans below the containers to form refrigerant compartments below the roof and adjacent the side walls of the car. It is also common to provide vertical flues associated with the side walls and extending to near the floor. These flues serve as passages for the flow of refrigerated air from the refrigerant compartment to below the floor racks of the car so that it may circulate upwardly through the lading and also serve to drain liquid from the drip pans.

There are several types of refrigerant containers used in cars of this type, depending upon the refrigerant to be used. For fresh water ice or eutectic ice, a foraminous basket made from wire screen, expanded metal, or perforated plate, is suitable. A common type of container is a semi-brine tank having a foraminous upper portion to facilitate air circulation and an imperforate lower part for partial retention of brine. It is sometimes desirable to retain all of the melted ice as a liquid, in which case the container would be a tank entirely imperforate and preferably sealed. An imperforate tank is also desirable when the refrigerant is dry ice because the sublimed gas is harmful to some types of lading and because the rate of sublimation may be controlled by controlling the pressure within the tank.

The drip pans underneath the containers have two important functions. They provide flues below the containers for the circulation of cooled air to the side flues and they also protect the lading against drip from the containers. The drip may be melted refrigerant from a foraminous basket or from a semi-foraminous container. If an imperforate tank is used with brine or dry ice as the refrigerant, there is considerable condensation on the cold walls of the tank.

This condensation may be a source of the above mentioned drip.

It is usually desirable to provide means by which the refrigerant containers may be cleaned or repaired. A common expedient is to provide drip pans which are removable, or preferably,

hinged to the car structure to facilitate handling. If the drip pans are made to extend continuously from end to end of the car, the handling would be very difficult. To overcome this objection, they may be constructed in short sections but then means must be provided to prevent drip through the spaces between adjacent drip pans.

It is an object of this invention to provide means to prevent dripping of liquid through the spaces between adjacent drip pans. A further object of the invention is to provide said means so that it will not interfere with the flow of liquid and cooled air toward the side flues. In other words, the drip-prevention means should not interfere with the refrigeration efficiency. It is a still further object to provide said drip-prevention means in such a form that it will not interfere with the removal of drip pans for cleaning and repairing purposes.

Other advantages and objects of my invention will be apparent from the following detailed description by referring to the drawing in which:

Fig. 1 is a partial transverse section of a refrigerator car equipped with foraminous refrigerant containers.

Fig. 2 is a longitudinal section of the car shown in Fig. 1. The section is on line 2—2 of Fig. 1.

Figs. 3 to 6 show modified constructions.

The parts of the refrigerator car shown in Fig. 1 are side plate 2; side sheathing 3; side lining 4; false wall 5; providing the flue 6; roof 7; running board 8; hatch frame 9 surrounding the hatch 10; ceiling 11; refrigerant container 12 having a bottom 13; side walls 14 and end walls 15; center duct 16 formed by the wall 17; drip pan 18; and insulation 19. The drip pan 18 preferably comprises a wood supporting and insulating member 20 and a metallic protecting member 21. The drip pan 18 may be hinged at (22) to the wall 5 and provided with a latch 23 at the wall 17, although the invention is not limited by this arrangement. For example, a latch could be substituted for the hinge 22, in which case the drip pan could be entirely removed.

The refrigerant containers 12 are spaced apart to provide the duct 29 and the invention consists essentially of providing means to prevent liquid dripping from the containers 13 through the space 30 between adjacent drip pans 18. As heretofore explained, it is advantageous to provide the drip pan in several sections to facilitate the handling thereof. The space 30 between the sections must be sufficient to permit one section to clear the adjacent section during the swinging or removal thereof.

As shown in Fig. 2, a member 31 is secured to adjacent containers above the space 30 to prevent dripping therethrough. The member 31 extends substantially the width of the container 12, width being defined as the distance between the side walls 14 of a container 12.

Fig. 3 shows a modified design in which the metallic drip pan members 21 are provided with upstanding flanges 35. An inverted channel-shaped member 36 is secured to the containers 12 as shown. The downwardly projecting flanges 37 of the channel 36 preferably extend below the tops of the upstanding flanges 35, thus effectively preventing dripping and splashing through the space 30.

The modification shown in Fig. 4 may be used when the distance between adjacent containers 12 is relatively great. The member 40 is shown having an imperforate part 41 overlying the space 30 and projecting parts 42 for attachment to the containers. The parts 42 may be made separately and attached to the part 41, as shown in the drawing, or they may be formed integral therewith. This construction may be used when it is desired to save weight and when it is felt that a relatively wide imperforate member 40 would be detrimental to air circulation. In Fig. 4 the metallic drip pan members 21 are shown formed with upstanding flanges 43 and reflanges 44. The reflanges 44 tend to prevent liquid splashing over the flanges 43 and through the space 30.

Fig. 5 shows a modification similar to Fig. 3 but with the addition of the reflanges 47 to the upstanding flanges 35 of the drip pan protecting members 21.

In Fig. 6 a supporting member 50, which is similar in function to the projecting parts 42 of Fig. 4, extends between adjacent containers 12. An inverted channel member 51 is supported, preferably by the member 50, so as to overlie the upstanding flanges 53 of the drip pan protecting members 21.

The drawing should not be construed as limiting the invention. Although a foraminous basket-type refrigerant container is shown, the members 31, 36, or 40 could be equally well adapted to other types of containers, some of which have been heretofore described. The member 31 could be secured to the ends of the containers or the member 36 to the bottoms.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator, spaced apart refrigerant containers with an air duct therebetween, a drip

pan spaced below each container for draining liquid therefrom, the adjacent edges of said drip pans being below said duct, and means to prevent liquid from said containers from dripping between said adjacent edges, said means comprising a member over said adjacent edges and supported by said containers with means on each side of said member for air communication between said duct and the spaces below said containers. 5

2. In a refrigerator, spaced apart refrigerant 10 containers with an air duct therebetween, a drip pan below each container for draining liquid therefrom, the adjacent edges of said drip pans being below said duct and provided with upstanding flanges, and means to prevent liquid from said 15 containers from dripping between said adjacent edges, said means comprising an inverted channel member supported by said containers and overlying said adjacent edges.

3. In a refrigerator, spaced apart refrigerant 20 containers with an air duct therebetween, a drip pan below each container for draining liquid 25 therefrom, the adjacent edges of said drip pans being below said duct and provided with upstanding flanges, and means to prevent liquid from said containers from dripping between said adjacent edges, said means comprising a member over 30 said adjacent edges and supported by said containers.

4. In a refrigerator, spaced apart refrigerant 30 containers with an air duct therebetween, a drip pan below each container for draining liquid 35 therefrom, the adjacent edges of said drip pans being below said duct and provided with upstanding flanges having inwardly projecting reflanges, and means to prevent liquid from said 40 containers from dripping between said adjacent edges, said means comprising a member over said adjacent edges and supported by said containers. 40

5. In a refrigerator car having a roof and a wall, a pair of spaced apart refrigerant containers below said roof and adjacent said wall, an air flue associated with said wall below said containers, a drip pan spaced below each of said 45 containers to form a space therebetween, the adjacent edges of said drip pans being below the duct between said containers, means whereby air is circulated from a part of the car remote from said wall through said duct and said space 50 to said flue, and a member supported by said containers above the adjacent edges of said drip pans to prevent liquid dripping therebetween. 50

6. A structure as defined in claim 2 wherein the lower edges of the depending flanges of said 55 channel member are lower than the upper edges of the upstanding flanges of said drip pans.

7. A structure as defined in claim 2 wherein the upstanding flanges of said drip pans are provided with inwardly projecting flanges. 60
